UNITED STATES PATENT OFFICE.

ALLEN A. BOWSER, OF FORT WAYNE, INDIANA ASSIGNOR TO S. F. BOWSER & COMPANY, INC., OF FORT WAYNE, INDIANA.

CONTROLLING DEVICE FOR PUMPING SYSTEMS.

1,107,887.

Specification of Letters Patent. Patented Aug. 18, 1914.

Application filed September 16, 1912. Serial No. 720,469.

To all whom it may concern:

Be it known that I, ALLEN A. BOWSER, a citizen of the United States, residing at Fort Wayne, in the county of Allen and State of Indiana, have invented certain new and useful Improvements in Controlling Devices for Pumping Systems, of which the following is a specification.

My invention relates to means for controlling liquids in pumping systems where the source of liquid supply and the pumping mechanism are at relatively different heights, and the primary object of my invention is to provide improved means in such systems for automatically sealing the passage between the source of supply and the pumping mechanism when the system is not in use to prevent the liquid from flooding the pump or flowing from the pump by gravity, as the case may be.

Other objects of my invention will appear hereinafter.

My invention consists in the features of novelty exemplified in the construction, combination and arrangement of parts herein described, and shown in the accompanying drawings which illustrate one embodiment of my invention, and more particularly pointed out in the appended claims.

In the drawings, Figure 1 is a view of a representative pumping system embodying my invention and involves a system where in the supply tank is elevated above the discharge point of the pump. Fig. 2 is an enlarged view partly in section and partly in elevation of that portion of Fig. 1 involving my invention. Fig. 3 is a sectional view similar to Fig. 1, illustrating the application of my invention to a system wherein the pump is elevated above the supply tank.

The pumping mechanism, supply tank and various pipings and connections shown in the drawings are typical of a liquid pumping system which is more particularly adapted to the handling of gasoline or oils for automobile service, and although I have shown my invention in the preferred form after having obtained an understanding of my invention from the disclosures herein made it will be apparent that my invention is equally applicable to other systems wherein similar requirements are to be met, without departing from the spirit and scope of the invention.

Referring to the drawings, it will be seen

that the mechanism A represents a pumping device which, although illustrated as being of the self-measuring type, may be of any suitable or desired construction adapted for the purpose. This pump is arranged to draw liquid from a tank B, which in the particular arrangement shown in Figs. 1 and 2, is elevated above the discharge nozzle C of the pump. This tank is of course representative of any suitable vessel or receptacle adapted to serve as a source of liquid supply. The pump A is connected with the supply tank by means of piping D, and in the construction shown this pipe D enters the tank B from its upper side and extends to the bottom of the tank in order that all of the liquid in the tank may be drawn therefrom, this being a usual method of arranging pumping systems of this character. The end portion D¹ of the piping connects with the pump at the base thereof in any desired manner. Although I have illustrated the tank B as being elevated above the pumping mechanism it is obvious that the relative heights of the pump and tank may be arranged as desired. For instance, the tank may be located below the discharge level of the pump A. In systems of this character considerable trouble is experienced when the system is not in use by reason of the pump becoming flooded with liquid or being deprived of liquid, depending upon the relative heights of the pump and supply tank. This trouble is due to the fact that the valves leak. In systems like that shown in Fig. 1, where the tank is elevated above the pump, the head of liquid will by the action of gravity seep or leak through the valves and discharge nozzle E and will not only flood the pump but will drip from the pump and be lost. In systems where the pump is above the tank a similar action takes place in the sense that by reason of leaky valves the oil flows back to the tank and thereby leaves the pump. I have provided a device which positively prevents the flow of oil in either direction after the pump has ceased operating. This device in Fig. 1 is indicated generally by the letter F and is interposed in the pipe line D between the tank and pump. Referring more particularly now to Figs. 2 and 3, it will be seen that this device preferably comprises a relatively long hollow tube or pipe G, having enlarged hollow heads H and J at its upper and lower ends respectively. The lower

head J has an upstanding integral hollow portion J¹ through which the tube G passes and in which it is firmly secured. The interior of this upstanding portion J¹ is enlarged sufficiently to provide an annular space N between the tube G and itself and it serves as a suitable means to which may be fastened a portion D² of the supply pipe leading from the tank. The lower head J, as before mentioned, is hollow and is adapted to contain a pool or quantity of mercury M, and a removable screw plug J³ is provided in the bottom of this head for the purpose of removing the mercury or for cleaning purposes whenever desired. The lower end G¹ of the vertical tube G projects downwardly into the mercury pool to some distance below the upper level thereof. The upper head H also has a hollow upstanding portion H¹ to which the pipe D¹ is connected, this pipe also connecting directly with the pump as before explained.

When the pump is operating, the flow of liquid will be from the tank B through the piping D and D² into the hollow portion J¹ of the lower head. From thence it passes into an enlarged chamber J⁴ of the lower head and then up through the vertical tube G to a chamber H³ of the upper head. From here it passes into the hollow portion H² of the upper head and then through the pipe D¹ and pump. In passing through the chamber J⁴ of the lower head, however, the liquid must necessarily pass below the level of the mercury in order to enter the lower end G¹ of the vertical tube G and more or less of the mercury will be carried with the oil up through the tube G to the upper head, but on account of the enlarged chamber H³ of the upper head the mercury will not pass above the head, but will tend to flow laterally into this chamber and allow the oil to pass beyond it into the pump. As soon as the pumping operation is finished, however, the mercury being heavier than the oil or liquid, will run back down the tube G and settle quiescently in the lower head and seal the end of the tube G. The passage through the lower head J between the pipe D² and the tube G is thus automatically closed, and even though there be considerable head of liquid from the elevated supply tank the action of gravity on this head of oil will not be sufficient to cause the oil to pass into the tube G. So far I have described this mercury sealing device in connection with a system where the tank is elevated above the pump and it is therefore desired to prevent the flooding of the pump. In Fig. 3, however, I have indicated the device as applied to a system where the tank is located below the pump and in this system it is desired to prevent the liquid from gradually leaking back into the tank and away from the pump when the pump is not in operation. In this

figure the pipe L leads from the lower head J of the mercury valve to the pump and the pipe O leads from the tank or source of supply to the upper head H of the valve device. Otherwise the valve structure is the same as that shown in Fig. 2. In this figure, however, the oil is drawn downwardly through the head H, tube G, and through the mercury pool or bath M, and thence into cavity N of the upstanding portion J¹ of the lower head. From here it passes through the pipe L to the pump. It will thus be seen that after the pump has operated, the quantity of liquid remaining in the pipe L between the pump and the head cannot seep back into the tank through the mercury seal and in this manner the liquid is maintained in the pipe L right up to the pump so that the instant the pump is operated it will immediately cause a flow of liquid therefrom. This is particularly advantageous when the self-measuring types of pumps are used since the pump must commence to measure and discharge liquid the instant the pump commences to operate.

What I claim is:

1. The combination of a pump, a tank, a pipe connection from said pump to the tank, and a mercury valve interposed between the pump and the tank.

2. The combination of a pump and a tank disposed at different levels, a pipe connection therebetween, and a mercury valve interposed between the pump and the tank.

3. In a liquid pumping system, the combination of a pump, a tank, a pipe connection from said pump to the tank, and a mercury valve interposed between the pump and the tank.

4. In a liquid pumping system, the combination of a pump and a tank disposed at different levels, a pipe connection from the pump to the tank, and a mercury valve in said pipe connection.

5. In a liquid pumping system, the combination of a pump, a tank, a pipe connection from said pump to the tank, and a mercury valve disposed between the pump and the tank, said valve having an upper and a lower chamber which communicate with each other through a single pipe.

6. In a liquid pumping system, the combination of a pump and a tank disposed at different levels, a pipe connection therebetween, and a mercury valve in the pipe connection, said mercury valve having an upper and a lower chamber with communication therebetween through a single pipe.

7. In a liquid pumping system having a pump, a tank disposed at a different level from said pump, and a pipe connection therebetween, a mercury valve in said pipe connection having an upper and a lower chamber, said lower chamber containing a mercury bath and the two chambers commu-

- ninating through a single pipe which extends downwardly through the lower chamber below the upper level of said mercury bath.
- 5 8. In a liquid pumping system having a pump, a tank and pipe connection between the pump and the tank, a mercury valve in said pipe connection, said valve having an upper and a lower chamber, said chambers communicating through a single pipe which extends downwardly below the upper level of a mercury bath contained in said lower chamber, and said lower chamber containing sufficient mercury to maintain against the force of gravity any difference in level of the liquid contained in said liquid pumping system.
- 10 15. In a liquid pumping system having a pump and a tank disposed at different levels
- with pipe connection therebetween, a mercury valve in the pipe connection having an upper and a lower chamber, said chambers communicating through a single pipe which extends downwardly below the upper level of a mercury bath contained in said lower chamber, and said lower chamber containing sufficient mercury to maintain against the force of gravity any difference in level of the liquid contained in said liquid pumping system. 20 25 30

In testimony whereof I have signed my name to this specification, in the presence of two subscribing witnesses, on this 6th day of September A. D. 1912.

ALLEN A. BOWSER.
